UNITED STATES PATENT OFFICE.

DANIEL WILLIAM McC LAUGHRY, OF FOX LAKE, WISCONSIN.

CORNER-SHIELD FOR WAGON-BOXES.

SPECIFICATION forming part of Letters Patent No. 628,834, dated July 11, 1899.

Application filed February 11, 1899. Serial No. 705,298. (No model.)

To all whom it may concern:

Be it known that I, DANIEL WILLIAM McC LAUGHRY, of Fox Lake, in the county of Dodge and State of Wisconsin, have invented 5 a new and Improved Corner-Shield for Wagon-Boxes, of which the following is a full, clear, and exact description.

The object of the invention is to provide a simple and effective device capable of attachment to any wagon-box and adapted to protect the faces and ends of the side-boards, so that they will not be injured or become marred and to hold the end-boards of the box in place.

The invention consists in the novel construction and combination of the several parts, as will be hereinafter fully set forth, and pointed out in the claim.

Reference is to be had to the accompanying drawings, forming a part of this specification, 20 in which similar characters of reference indicate corresponding parts in all the figures.

Figure 1 is a perspective view of one corner of a wagon-box, illustrating the application of the improved device to an end of a side-board of the box and an end of an end-board. Fig. 2 is an inner face view of the device. Fig. 3 is an edge view of the device, and Fig. 4 is a horizontal section taken practically on the line 4 4 of Fig. 3.

30 A shield is adapted to be used at each end of each side-board of a wagon body or box. A represents the bottom of a wagon-box; B, one of the side-boards; C, the band-iron that is usually secured upon the upper edge of a side-board of a wagon-box; D, an end-board, and E the improved corner-shield. The shield is made of metal, either cast, forged, or otherwise shaped, and each shield is of box-like construction, comprising an inner side 10, an 35 outer side 11, a top 12, and a rear end 14, the space between the sides being such that the shield may snugly fit to the side faces of the side-board of the wagon-box, so that when the shield is placed in position upon the side-board the lower edge of the inner face of the shield may rest upon the bed of the wagon-box; but, if desired, the outer side of the shield may be of greater height.

An extension 13 is provided in the top 12 at 40 the inner or open edge of a shield when the band-iron C is employed in order that the end of the band-iron may be received neatly with-

in the shield. The outer face or side 11 of the shield is provided with a reinforcement 15 at its outer lower corner, as shown in dotted 55 lines in Fig. 2 and in positive lines in Fig. 3, so that should a wheel of the vehicle engage with the shield it will not wear said shield to any appreciable or detrimental extent.

Parallel vertical flanges 17 are produced 60 upon the inner side of the shield E, forming a space 18, adapted to receive the end of an end-board D of the wagon body or box, which end-board, when shields are secured on the wagon-box, can be readily slipped into the 65 spaces 18 and when so placed will be held firmly in position. A shield is secured to a side-board by passing bolts, rivets, or screws through apertures 16, produced in the sides of the shield adjacent to its inner or open 70 edge, and a vertical rib 19 is formed upon the inner face of each shield near its inner edge, each rib 19 being provided with a reduced section 19^a, extending below the lower edge of the shield, and preferably the reduced section 75 19^a of the rib is threaded at its lower end to receive a nut 20, as shown in Figs. 2 and 3.

When a shield is in position upon a side-board of a wagon-box, the lower end of the rib 19 will bear upon the bed of the wagon-body; but the reduced section 19^a of the rib is carried through the bed of the wagon-body, so that when the nut 20 is screwed thereon to an engagement with the under side of the wagon-bed, the attachment thus provided 80 85 will effectually prevent the shield from leaving the side-board should the fastening devices passed through the apertures 16 become loosened or injured.

The locking-bar 21^a, usually passed longitudinally at the outer face of an end-board, is introduced at its ends into openings 21 made in the shields. The openings 21 in each shield are in transverse alinement, and the opening 21 in the outer face of a shield has 95 its wall threaded, and in order to protect the shields from injury when tension is brought to bear on the locking-rods 21^a the outer face of the shield around the outer opening 21 is reinforced, as shown at 22 in the drawings. 100

Having thus described my invention, I claim as new and desire to secure by Letters Patent—

A corner-shield for wagon-boxes, consist-

ing of an inner and an outer plate, a top connecting-section for the two plates and an outer end connecting-section for said plates, the space between the side plates being adapted to receive an end of a side-board of a wagon-box, the inner plate of said shield being provided with vertical flanges adapted to receive between them an end of an end-board of a wagon-box, the inner face of the inner plate being likewise provided with a rib extending to the lower edge of the side plate and provided with a reduced section extending below the edge of the said inner side plate, and

the reduced section of said rib being adapted to receive a nut, the side plates of the shield being provided with apertures to receive fastening devices and apertures to receive an end of a locking-bar for an end-board, said shield being further provided with a wheel-guard upon the outer face of its outer plate, for the purpose described. 15 20

DANIEL WILLIAM McC LAUGHRY.
